HOTEL GUEST LETTER AND MESSAGE BOXES

Sholem I. Mirkin, Cleveland, Ohio

Application March 29, 1954, Serial No. 419,328

1 Claim. (Cl. 232—34)

This invention relates to hotel guest mail and message boxes, and the main object is the provision of certain new and useful improvements in the construction of such boxes whereby greater convenience and security result for the guests and the hotel clerk's duties and cares are substantially lessened.

The above broad as well as additional and more specific objects will be clarified in the following description wherein characters of reference refer to like-numbered parts in the accompanying drawing. It is to be noted that the drawing is intended solely for the purpose of illustration and that it is therefore neither desired nor intended to limit the invention necessarily to any or all of the exact details of construction shown except insofar as they may be deemed essential to the invention.

Referring briefly to the drawing,

Fig. 1 is a perspective view of a hotel guest mail and message box embodying the improvements involved in the present invention, with parts broken away and partly in section.

Fig. 2 is a sectional view taken on the line 2—2 of Fig. 1.

Fig. 3 is a fragmentary perspective view of the rear, or innermost, end of the box.

Fig. 4 is a sectional view taken on the line 4—4 of Fig. 2.

Fig. 5 is a fragmentary perspective view, with parts broken away and partly in section, showing the front or outermost end of the box.

Fig. 6 is a sectional view taken on the line 6—6 of Fig. 4.

Fig. 7 is a sectional view taken on the line 7—7 of Fig. 2.

Referring in detail to the drawing, the box comprises top wall or roof 10, bottom wall or floor 11, and side walls 12 and 13. A horizontal partition or shelf 14 is provided a short distance from the roof 10 to provide a compartment 15 into which letters and messages may be deposited by the clerk, and for convenience in removing the letters by the guest, a number of longitudinal slots 16 may be provided in the shelf 14, as will hereinafter be more fully referred to.

As is customary in hotels, rows and tiers of guest boxes are provided. However, in using boxes of the kind herein presented, they would be mounted, in rows and tiers, at right angles to and extending through a wall or partition positioned with one side facing the clerk in his room or compartment and with the other side facing the hotel lobby. Merely by way of illustration, such a partition is indicated in phantom at 17 in Fig. 4, to show that the front ends of the boxes are exposed on the left of the partition or wall, and the rear ends on the right; the front ends are exposed to the lobby side of the partition and are thus available to the guests, while the rear ends are exposed only to the clerk. To facilitate following the description, the front end of the box is indicated at 18, and the rear end at 19.

The end wall or closure 20 at the rear end 19 of the

2

box is provided with a horizontal slot 21 in alignment with and giving access to the compartment 15 but having a smaller depth than the latter and preferably provided along its lower edge with serrations 22; the low depth of the slot with or without the serrations makes it difficult or impossible for the clerk to extract a letter from the compartment 15 after he has inserted it through the slot 21. The rear wall 20 is further provided with a large opening 23, intermediate the height of which wings 24 and 24a are provided, integral with and at right angles to the wall 20.

A normally vertical plate 25 has aligned pins 26 and 27 extending from the side edges thereof intermediate its height. A threaded opening 29 in the wing 24 is in axial alignment with the pins 26, 27, and a plug 28 is screwed therethrough; the extremity of the pin 27 registers rotatably in an axial recess 30 in the plug. The extremity of the other pin 26 similarly registers rotatably in a recess 31, axially aligned with the recess 30, in the other wing 24a. The pins 26 and 27 are rigid in the plate. A pinion 32 of small diameter is rigid on the pin 26.

Normally spaced a short distance above the bottom 11 of the box, is a vertically movable horizontal floor 33, having, extending downward from its center point, a cylindrical peg 34 slidably mounted in an upstanding sleeve 35 on the floor, the lower end of the sleeve being unobstructed to provide an air vent 36.

At the front end 18 of the box, a vertically hinged door 37 is provided, and it further has a lock 38 for which the guest will have the key. A letter slot 39 is provided through the top of the door, normally closed by a horizontally suspended hinged flap 40 inside the box, the slot giving access to the letter compartment 15 so that a caller may insert a note or message for the guest. After opening the door 37, the guest may remove letters from the compartment 15, and as an aid thereto he may insert one or more fingers partway through the shelf slots 16 to urge the letters forward. Also, with the door 37 open, he may insert his room key and deposit it on the movable floor 33, which he will of course do on going out. To assure that the weight of the room key will move the floor downward the desired distance, for the purpose which will presently be set forth, the following mechanism is provided.

Two similar simple levers, having the form of a flattened S, are fulcrumed in pedestals 42 mounted on the box bottom 11. The inner end of each lever is forked, as shown at 43. Equidistant from the longitudinal median line of the floor 33, aligned horizontal transverse pins 44 are suspended, by brackets 45, a short distance from the floor 33. The forked end of each lever 41 engages one of these pins. The other or outer end of each lever 41 is slidably mounted in a passage 46 through a flat and relatively wide but thin weight 47; these outer ends of the levers are indicated at 41a. By means of long set screws 48 entering into contact with the ends 41a through the side of the weights 47, the weight may be positioned inward or outward from the fulcrum 42 as desired so as to obtain the proper balance against the weight of the floor, that is, to normally fall to the box floor 11 but, when the weight of the hotel key is added on the floor 33, to rise.

A vertical partition 49 is rigidly suspended from the shelf 14 near the rear end of the box, and its lower end is provided with spaced teeth 50 adapted to ride through spaced openings 51 in the floor 33 as the latter rises or falls. The partition 49 is a sufficient distance forward of the plate 25 to enable the latter to swing through an arc of 180 degrees, or rather, to rotate freely. On the rear end of the floor 33, at one side, an upstanding ear 52 is provided, in which the lower extremity of an upstanding slightly curved rack 53 is pivotally mounted,

and a spring 54 urges the rack into engagement, at all times, with the pinion 32. Thus, as the floor 33 falls from the position shown in Figs. 2 and 5, the rack will rotate the pinion and hence also the plate 25. The plate 25 has on one side the legend "Empty" or an equivalent, and on the other side the legend "Occupied" or an equivalent. The distance the floor 33 can move downward is limited by the sleeve 35, Fig. 6. With the floor 33 in its lower limit position, the side of the plate bearing the legend "Occupied" should be exposed to the clerk, that is, through the opening 23, and this will occur when the room key, not shown, lies on the floor 33. However, it is advisable to provide an adjustable limit stop for the downward movement of the floor 33 short of the sleeve 35, and this is provided by an extension arm 55 on one of the pedestals 42, preferably the forward one, having an approximately vertical screw 56 threaded therewith from the bottom. Access to the screw is attained through an aligned opening 57 in the box floor 11. Thus, the screw 56 is so positioned that when the floor 33 is weighted with the room key, the floor will descend only a sufficient distance to turn the plate through an arc of 180 degrees from its normal position in which it reads "Occupied." In other words, when the key is in the box and the plate reads "Vacant" it signifies that the guest is not in the hotel, and when the key is not in the box the plate reads "Occupied" to signify to the clerk that the guest is in his room. Hence, if anybody asks for the guest the clerk can see at a glance whether the guest is in or not.

The normal position of the floor 33, lacking the added weight of the room key, is maintained to hold the plate in position reading "Occupied" to the clerk, once the weights 47 have been properly positioned. The balance between the weighted levers 41 and the plate is maintained at all times, so that when the key is lifted off the floor 33 and removed by the guest, the floor rises and the plate 25 swings through 180 degrees to read "Occupied."

As an added assurance that a guest will not take the room key out of the hotel with him, it would be desirable to have it attached to a good-sized block, and wherever the weight of the key is referred to above it of course includes the weight of such a block or the like.

I claim:

A box comprising top and bottom walls and side walls, the front end of said box having a door normally closing the same, said box having a vertically movable raised platform above said bottom wall, adjustable yieldable means normally supporting said platform at a given distance above said bottom wall, the weight of said platform and the upward force of said yieldable means being normally in balance whereby upon the addition of a small weight such as, for example, that of a room key, on said platform said platform is urged downward against said upward force, the rear end of said box being open and having a plate rotatably mounted therein on a transverse shaft intermediate the height of the plate, means partly on said platform and partly on said shaft for rotating said plate upon vertical movement of said platform, said plate being adapted to have legends on both sides thereof and being positioned vertical with one of the sides thereof facing rearward when said platform is in said normally raised position, means limiting the downward movement of said platform, said plate in the lowermost limit of the platform being positioned with the opposite side thereof facing rearward, said box having a horizontal support rigid therein near the top thereof, said support having a vertical partition extending downward therefrom near but spaced from the rear end of the box to a level below the level of the lowermost position of the platform, said platform having a plurality of transversely spaced openings therethrough in the plane of said partition, the lower end of said partition having teeth formed thereon slidably registering in said transverse openings, said partition thus at all times blocking access into the box through the rear end thereof regardless of the angular position of said plate with respect to the vertical.
